(57) **CLAIM**

The ornamental design for a beverage container as shown and described.

DESCRIPTION

FIG. 1 is a first perspective view of the beverage container design;

FIG. 2 is a second perspective view thereof;

FIG. 3 is a first side view thereof;

FIG. 4 is a second side view thereof;

FIG. 5 is a third side view thereof;

FIG. 6 is a fourth side thereof;

FIG. 7 is a top view thereof;

FIG. 8 is a bottom view thereof;

FIG. 9 is a third perspective view thereof, showing the spout in an upright position in a configuration of use; and,
FIG. 10 is a fourth perspective view thereof, showing the lid removed in a configuration of use.

The dashed lines depict portions of the beverage container that form no part of the claimed design.

1 Claim, 10 Drawing Sheets
